UNITED STATES PATENT OFFICE.

GEORGE D. BOWEN, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

LOCOMOTIVE-PILOT.

1,072,303.

Specification of Letters Patent.

Patented Sept. 2, 1913.

Application filed July 25, 1912. Serial No. 711,499.

To all whom it may concern:

Be it known that I, GEORGE D. BOWEN, a citizen of the United States, residing in Philadelphia, Pennsylvania, have invented 5 certain Improvements in Locomotive-Pilots, of which the following is a specification.

The object of my invention is to improve the construction of pilots for locomotives and this object I attain by making the pilot 10 from a sheet metal plate bent into form and suitably braced, thus dispensing with the usual cumbersome pilot made of bars.

In the accompanying drawings:—Figure 1, is a plan view of my improved pilot; Fig. 15 2, is a front elevation thereof; Fig. 3, is a longitudinal sectional view on the line 3—3, Fig. 1, and Fig. 4, is a perspective view of the sheet metal plate forming the facing of the pilot.

20 B is the bumper beam at the forward end of the locomotive and of the ordinary construction.

b is the draw head secured to the bumper beam.

25 A is the pilot made of sheet metal and bent into the form illustrated in Fig. 4, having a central inclined portion a, inclined side portions a' and vertical portions c, c. The latter extend above the upper edges of the 30 portions a', a'. The projecting portions c are bolted firmly to the bumper beam B, as shown.

c', c' are inturned flanges, which project under the bumper beam and are secured 35 thereto by right angled plates E. These plates extend part way down the flange, as illustrated in Fig. 3, and vertical bolts secure these plates to the bumper beam.

At the lower end of the pilot is a vertical 40 flange e and an inturned flange e', which materially strengthen the pilot, and in order to reinforce the nose of the pilot I provide a plate f, which is riveted to the inturned flange and at each edge I also provide a reinforcing plate f', which is secured to the inturned flange by bolts or rivets.

D, D are braces, one at each side of the center of the pilot. These braces are inclined and are secured by bolts to the lower 50 flange e' of the pilot and extend either to the back of the bumper beam or some distance to the rear of the bumper beam and are secured to longitudinal stringers, according to the type of the pilot employed. These 55 braces are wide so that two or more bolts

can be used to secure them in place and they are beveled at their outer ends so as to fit snugly against the inclined surface of the pilot.

It will thus be seen that I am enabled to 60 make a pilot with very few parts and to make the body of the pilot of sheet metal bent into shape and suitably braced.

The pilot can be readily secured to the bumper and the braces may extend beyond 65 the bumper or to a point at the rear of the bumper; two or more braces being used, according to the type of locomotive to which the invention is applied. In some instances the flange e' may be bent outward instead of 70 inward as shown.

I claim:

1. A pilot for locomotives made of a sheet metal plate bent to form two inclined side portions and two vertical portions at the 75 rear of the pilot terminating at the inclined side portions, said vertical portions extending above the upper edge of the said inclined side portions and spaced apart at the center and adapted to be secured to the bumper 80 beam of a locomotive.

2. A pilot for locomotives made of a sheet metal plate bent to form two inclined side portions, vertical portions at the rear of the pilot extending to the inclined side portions, 85 a vertical flange depending from the lower edge of the inclined portions, the vertical portions extending above the upper ends of the side portions and spaced apart and adapted to be secured to the bumper of a 90 locomotive.

3. A pilot for locomotives made of a sheet metal plate bent to form a central inclined portion and two inclined side portions, a vertical portion at the rear end of each side 95 portion, said vertical portions extending above the upper end of the side portions and adapted to be secured to the bumper beam of a locomotive; and vertical inturned flanges at the outer edge of each vertical portion extending from the lower edge of the pilot and projecting under the bumper beam.

4. A pilot for locomotives made of a sheet metal plate bent to form a central inclined portion, two inclined side portions; a vertical portion at the rear end of each side portion, said vertical portions extending above the upper edge of the side portions and spaced apart; a vertical flange depend- 105 110

ing from the lower edge of the central inclined portion and inclined side portions; and an inturned flange at the rear end of the pilot projecting rearwardly from the 5 outer edge of the rear vertical portion, said flange connecting with the vertical flange at the lower edge of the pilot.

In testimony whereof, I have signed my name to this specification, in the presence of two subscribing witnesses.

GEORGE D. BOWEN.
